UNITED STATES PATENT OFFICE.

JOHN P. RICHARDSON, OF CAMBRIDGE, ASSIGNOR TO THE MASON & HAMILIN ORGAN AND PIANO COMPANY, OF BOSTON, MASSACHUSETTS.

PIANO-FORTE.

SPECIFICATION forming part of Letters Patent No. 388,308, dated August 21, 1883,

Application filed June 16, 1885. Serial No. 168,874. (No model.)

To all whom it may concern:

Be it known that I, JOHN P. RICHARDSON, of Cambridge, in the county of Middlesex and State of Massachusetts, have invented certain new and useful Improvements in Piano-Fortes, of which the following is a full, clear, and exact description.

This invention relates to improvements in piano forte actions, and more particularly to actions for upright piano-fortes; and the invention consists of certain construction and arrangement of parts in combination with a piano-forte action, all substantially as herein-after fully described.

15 In the accompanying plate of drawings is illustrated the present invention, Figures 1 and 2 representing in side elevation an action of an upright piano-forte having the present invention combined therewith, Fig. 1 representing all parts in their normal position or at rest, and Fig. 2 representing some of the parts as having been moved into the position desired for producing the soft tones according to this invention when playing the instrument; 25 and Figs. 3, 4, and 5 represent detail side views of modifications.

In the drawings, A represents the key-frame of a piano-forte action, to which the usual end uprights (not shown in the drawings) of the 30 action are attached and secured, and to which the horizontal rail B is secured at its ends in the usual manner for supporting the various parts of the action. C is the key, pivoted at a to the key-frame A. D is the jack, pivoted at b to a horizontal lever, E, in turn pivoted at c to a flange, F, on the rail B. G is the hammer on the stem H of the butt J, pivoted at d to the flange K, secured to the rail B, the hammer-butt J bearing and resting by its 35 shoulder f on the upper end, g, of the jack D. L is the back catch, attached to the lever E, and M the damper, pivoted at h to the flange N, secured to the rail B. P is the string; Q, the push rod or stem, pivoted at l to an arm, R, 40 pivoted at m to a flange, S, secured to the rail T of frame A, the arm R resting by its free end n on the key C, all as usual in upright-piano-forte actions, in connection with a few other parts not deemed necessary to refer to, and all 45 needing no particular description herein or as to their operation, as they are common and

well known, except so far as the present invention is connected therewith.

The push-rod has pivoted to it at its upper end, at r, a block or plate or segment, U, extending upward therefrom, and on which pivot it can swing forward and backward, its upper edge, s, preferably being in the arc of a circle which is eccentric to its pivot r, the length of the end or corner t from its pivot r being longer 55 than the length of its end or corner u to said pivot.

The jack-lever rests by its under side v on the edge s of the block, and when in the position shown in Fig. 1 it rests on the end u of 60 the hammer, then being in its true and normal position for the proper working of the action and resting on its jack, and through the jack and rod Q on the key.

w is a piece of cloth or felt between the lever 70 E and the block U, one end of it being secured to the block at t and its other end to the lever by any suitable adhesive material or in any suitable manner, which prevents noise between the parts and secures permanent connection of 75 the same.

Pivoted at x to the rod Q by one end is an arm, V, in turn pivoted by its other end to one end of a flange or arm, W, secured to a rail, Y, which rail is connected by arms Z to a 80 rail, A², adapted to turn by its ends in suitable bearings in the end uprights.

B² is a bar or rod connected to and projecting from the swiveling rail A² and by its end y by a slot, b², over a pin, a², on the vertical rod C², which rod C² extends downward and is connected to the usual pedal of the piano-forte for operation thereof by the foot of the player, as usual. Pressing the foot on the pedal raises the vertical rod C², and through 85 its arms B² swings the rail A², carrying its rail Y forward, and thus the upper end of the push-rod forward, swinging on its pivot l, its block U rolling, as it were, by its edge s on the under side of the jack-lever, bringing its corner 90 or end t in line with the rod Q, which by its increased length from the pivot r over the length at u raises the lever E and its jack, and thus the hammer, into the position shown in Fig. 2, and in which position, if the key is 95 played, the tone produced by the string from the blow of the hammer thereon will be di-

minished in power and sound, and thus softened, and at the same time the hammer is in connection by its jack, jack-lever, and push-rod with the key.

5 D² is a horizontal rail back of the hammer-stems H, against which they fall in the playing of the action, and serving as a safeguard against the hammers falling back too far to prevent the jacks properly taking hold of the hammer-butts to again cause the hammer to strike the string in repeating the blow on the key, and in moving the hammers forward into the position shown in Fig. 2 to produce the soft tones, as described, it is essential that this 15 rail D² should be moved forward correspondingly for its proper use, and such movement is accomplished as follows: Attached to each end of the rail and projecting downwardly is an arm, E², each arm being pivoted at d² to its 20 respective end upright. Connected to one arm E² of this rail is an arm, F², which arm F² has a slot, f², engaging with a pin, g², on the vertical rod C² in a similar manner to the arm B² of rail A². As the rail A² is operated by 25 the rod C² to raise the hammers, the rail D², through its arm E², is swung forward at the same time into proper position to support the hammers, as described, and as it is swung forward it also assists in raising the hammers.

30 In Fig. 3 is shown a modification of the rod Q, being pivoted at its upper end, at h², directly to the jack-lever E, and the block U being reversed and pivoted at l² to the lower end of the rod Q, its circular edge s resting 35 and operating on the upper surface of the key A in a similar manner to its operation on the lever E when secured at the upper end of the rod, t being its long arm and u its short arm.

By an arrangement as herein described the 40 hammers, through the jacks and push-rods, rest at all times on the keys, whether in their normal positions or in their changed or soft-stop position, or in changing from one to the other, thus securing a constant sensitiveness 45 of the action and not injuring or affecting the touch; also, this arrangement of moving the push-rods under the jack-levers lengthens the fulerum or action of the jack-levers, lightening or diminishing the blow of the hammers 50 on the string, and in itself reducing the sound produced by the strings, which also accords with the natural tendency of the player when using the soft-stop to play with a lighter touch; also, by having the outer points, t u, of contact

and practical operation of the block U connected by an edge in the arc of a circle, a graduation of the blow given by the hammers will be secured, and consequent graduation of the loudness or softness of the tone produced by the strings by the player operating the 60 pedal to move the push-rod Q more or less, as desired.

As the ends t u of the block U are practically the principal operating parts of the block, it is obvious they need not be connected by the 65 edge s, but between the two points the block can be cut away, as shown in Fig. 5; but it is preferable to have the curved edge, s, connection, as in the operation of the same the parts work the easier and better. By this arrangement of lengthening out, as it were, the push-rod Z and preserving its connection with the keys and jacks and the jacks with the hammers the full movement or dip of the keys is also maintained, which is of importance, as in 70 this respect the touch and sensitiveness of the action is secured; also, the hammers can be raised into the necessary half-way positions to produce the soft tones by the operation of the rail D² alone, or in any suitable manner, and 80 the jacks moved or raised, as described, to preserve their connection with the hammer-butts in lieu of directly raising the hammers by the jacks, as described.

Having thus described my invention, what I 85 claim is—

1. In a piano-forte action, in combination, key C, push-rod Q, plate or block U, pivoted to said rod, jack D, and hammer M, for the purpose specified.

2. In a piano-forte action, in combination, key C, push-rod Q, plate or block U, pivoted to said rod and having a curved edge, s, eccentric to its pivot, jack D, and hammer M, for the purpose specified.

3. In a piano-forte action, in combination, key C, push-rod Q, plate or block U, pivoted to said rod, jack D, hammer M, and swiveling rail A², connected to said rod Q and to the pedal of the piano-forte, for the purpose specified.

In testimony whereof I have hereunto set my hand in the presence of the two subscribing witnesses.

JOHN P. RICHARDSON.
